UNITED STATES PATENT OFFICE.

JOHN WHITE, OF BEAUMONT, TEXAS.

RAIL-JOINT.

1,024,610.

Specification of Letters Patent.

Patented Apr. 30, 1912.

Application filed June 21, 1911. Serial No. 634,410

To all whom it may concern:

Be it known that I, JOHN WHITE, a citizen of the United States, residing at Beaumont, in the county of Jefferson and State 5 of Texas, have invented certain new and useful Improvements in Rail-Joints, of which the following is a specification, reference being had to the accompanying drawings.

10 This invention relates to rail joints and has for its object to provide rail ends which will serve to support each other and prevent sagging thereof.

15 A further object of this invention is to provide means whereby the rails will be securely locked together against displacement.

20 A further object of this invention is to have the outer portion of the ends of the rails comparatively strong, so that there will be less likelihood of them being distorted in use, at the same time these ends will be so arranged as to form a secure locking means for the rail.

25 Other objects of this invention will become apparent as it is more fully set forth.

30 In the accompanying drawings which illustrate by way of example an embodiment of this invention, Figure 1 represents a view in perspective of a rail end embodying this invention; Fig. 2 is a plan view of the upper end of the rail joint inverted; Fig. 3 is a plan view of the lower end of a rail joint, and Figs. 4 and 5 are detail sections on lines 4—4 and 5—5 respectively of Fig. 1.

Similar reference characters refer to similar parts throughout the drawings.

35 In the construction which is illustrated 40 in the drawings Fig. 1 represents an ordinary type of rail, which is preferably of a T design and which has one of its ends shaped into a somewhat U form, by spreading out and developing the web of the rail in the manner clearly shown in the drawings. The lower or flanged portion of the rail at this end is removed and this end is arranged to coöperate with the end of the adjacent rail and rest thereon in the manner clearly 45 shown in the drawings. The other rail end is suitably formed to take and rest underneath the first end and with its portions 2 lock the rail from longitudinal displacement.

50 Referring more particularly to Fig. 4 the outer portion of the rail 3 which is U shaped

is suitably drilled to receive a rivet, bolt or other fastening device so that this end when it is put over a projecting tongue 4 on the end of the adjacent rail can be fastened 60 securely thereto in the ordinary manner. Between the tongue 4 and the outer or channel end 2 of this rail end is left a space 5 so that the web extending from the U portion 3 of the first rail, which joins it to the 65 rib 6, will fit in this slot 5 and thereby lock the rail ends securely together.

70 In general one end of the rail has its flanged or bottom portion removed, its end portion U shaped, its legs or sides that form the U shape of a length arranged to rest upon the flanged or lower portion of the adjacent rail, which has its web 4 of a suitable size and position to be engaged with the sides of the U shape piece 3. The height 75 of the tongue 4 is sufficient to reach the lower portion of the other, so as to take the weight of the same thereon and transmit it to the sleepers, and also to prevent the joint from sagging when the train or 80 the like passes over it. The length of the sides of the channel end 2 is also sufficient to reach the end surface of the rail upon which they are disposed, and to take up the weight that is received by the rail, so that 85 it can be seen that the rail is very securely reinforced, for taking up the sagging action which the train tends to produce in the rail joints as it passes over them.

90 In practice the whole rail length will be produced in the usual manner, one end of the rail being formed so that it will form the upper surface of the rail joint, and its other end will be arranged to form the lower portion of the adjacent rail joint. In this 95 manner all the rails will be made alike and no trouble will be experienced in installing them, as would be likely to happen in case the rails were not formed in this manner.

100 It will be noted that this type of joints eliminates the necessity of a fish plate which is so essential for joints in the ordinary forms of rails, which in itself is a great advantage because it eliminates extra trouble and expense which is usually required.

105 Having thus described this invention it is claimed:

110 1. A rail joint comprising in combination the end of a rail having its end portion provided with a U-shaped web, the sides of said web extending down from the upper surface of the rail, a second rail end having its

end portion provided with a channel web arranged to engage with a portion of the first mentioned rail adjacent to the U shape portion and having a portion of its web removed in order to permit the base part of the U shape portion to be inserted therein, said end base having holes therethrough, and means disposed in said holes for securing said ends together.

- 10 2. A rail joint comprising in combination a rail end having its end portion U shaped, the base of said U shape being integrally formed with the web of said rail, said end having its flanged portion removed, another 15 rail end having its end portion channel shaped, said channel being arranged to embrace the sides of said web, and the web of said second end being removed for a short distance back from said channel portion in

order to permit the base portion of said U shaped piece to fit therein, the U shaped portion fitting over the web of said second end, its ends resting on the flanges of the second rail, and the web of the second rail extending to and supporting the upper portion of the U shape piece, the upper portion of said second rail being removed in order to permit the first mentioned rail to rest therein and to form a uniform rail surface, and said ends having holes therethrough and 25 means for securing said ends together.

In testimony whereof I hereunto affix my signature in the presence of two witnesses.

JOHN WHITE.
